UNITED STATES PATENT OFFICE.

WESLEY E. JORDAN, OF ERIE, PENNSYLVANIA.

TOP PLATE FOR STOVES.

1,337,774.

Specification of Letters Patent. Patented Apr. 20, 1920.

Application filed February 4, 1918. Serial No. 215,253.

To all whom it may concern:

Be it known that I, WESLEY E. JORDAN, a citizen of the United States, residing at Erie, in the county of Erie and State of Pennsylvania, have invented new and useful Improvements in Top Plates for Stoves, of which the following is a specification.

This invention relates to top plates for stoves and consists in certain improvements 10 in the construction thereof as will be hereinafter fully described and pointed out in the claims.

Top plates as heretofore manufactured when formed of cast metal with a continuous border have had supporting bars extending inwardly from the border but such bars have not been continuous because of the expansion or contraction incident to the intense heat directly over the burner which 15 causes the breaking of the plates. Continuous bars are of advantage in that they form a more stable support for articles resting thereon and also permit of the moving of the articles particularly small ones over 20 the plate with less obstruction.

The invention is illustrated in the accompanying drawings as follows:

Figure 1 shows a plan view of the top plate.

Fig. 2 a section on the line 2—2 in Fig. 1.

The plate is formed of the border made up of the sides 1 and the ends 2. Extending across the plate from border to border are the continuous bars 3. These bars are 25 parallel and sinuous, the bends permitting of the expansion of the bars and thus pre-

venting the breaking of the plate under the heat. This is particularly important where the burner, as 4, is under the central part of the plate so that the central 40 part is more intensely heated than the other parts. Such uneven heating is not the exception but the rule. While I have shown the bars of sinuous shape and in parallel relation I do not in the broader 45 phases of my invention wish to be so limited.

I have shown in the accompanying drawings the preferred form of my construction but I do not wish to be limited specifically 50 to the construction there shown and while I have shown the border of the plate forming my invention as the extreme edge of the plate I do not wish to be limited as to this.

What I claim as new is:—

1. The combination of a burner and a top plate subjected to the direct action of the burner and having a continuous border and continuous bars extending from border to border, said border and bars being formed 60 integrally of cast metal and said bars having expanding bends therein.

2. The combination of a burner and a top plate subjected to the direct action of the burner and having a continuous border 65 and continuous bars extending sinuously and parallel from border to border, said border and bars being formed integrally of cast metal.

In testimony whereof I have hereunto set 70 my hand.

WESLEY E. JORDAN.
